CLAIM

The ornamental design for a telephone, as shown and described.

DESCRIPTION

FIG. 1 is a front, left side and top, perspective view of a telephone according to our new design with the dashed areas being shown for environmental purposes and forming no part of this design;

FIG. 2 is a front perspective view thereof;

FIG. 3 is a left side perspective view thereof;

FIG. 4 is a right side perspective view thereof;

FIG. 5 is a top perspective view thereof;

FIG. 6 is a rear perspective view thereof; and,

FIG. 7 is a bottom perspective view thereof.
